SHIPPING BASKET

Walter R. J. WOOCK, Lodi, Calif.

Application December 19, 1949, Serial No. 6,725

Term of patent 14 years

(Cl. D58—4)

To all whom it may concern:

Be it known that I, Walter R. J. WOOCK, a citizen of the United States, residing at Lodi, in the county of San Joaquin and State of California, have invented a new, original, and ornamental Design for Shipping Basket, of which the following is a specification, reference being had to the accompanying drawing, forming a part hereof.

In the drawing:

Fig. 1 is a side elevational view of a shipping basket showing my new design, the lid being shown in raised position.

Fig. 2 is a cross sectional view thereof taken on the line 2—2 of Fig. 1, the lid being shown in closed position.

Fig. 3 is a reduced-size top plan view of the lid of the shipping basket, detached.

I claim:

The ornamental design for a shipping basket, as shown.

WALTER R. J. WOOCK.
